UNITED STATES PATENT OFFICE.

ORMUS E. BROWER, OF FILLMORE, UTAH.

GATE.

1,294,383.

Specification of Letters Patent. Patented Feb. 18, 1919.

Application filed May 25, 1918. Serial No. 236,508.

To all whom it may concern:

Be it known that I, ORMUS E. BROWER, a citizen of the United States, residing at Fillmore, in the county of Millard and State of Utah, have invented new and useful Improvements in Gates, of which the following is a specification.

The invention has particular reference to farm gates and the like and it seeks to provide as its principal object a gate which may be used to close the entrance to a field or to close a road way and yet to be conveniently operated by the occupant of a vehicle which approaches the gate from either side.

A further object of the invention is to provide a gate of this character which rises upwardly when being moved to the open position, the gate, when in full open position, springing diagonally from its normal vertical position.

A still further object is the provision of unique means for maintaining the gate in the open position.

A still further object is to provide a gate of this character which is simple in construction and yet durable and effective in operation.

Other and further objects will appear as the invention is set forth in detail in the following description.

The drawings illustrate and the specification describes what, at the present time is thought to be the most efficient embodiment of the invention. To this embodiment, however, the invention is not to be restricted. Continued use and practice may make manifest certain desirable changes or alterations and the right is claimed to make any which do not deviate from the scope of the annexed claims.

In the accompanying drawings:

Figure 1 is a perspective view of the improved gate,

Fig. 2 is a section on the line 2—2 of Fig. 1,

Fig. 3 is an enlarged detail view of the curved track and a portion of the adjacent post to which it connects,

Fig. 4 is a section on the line 4—4 of Fig. 1.

Referring to the drawings, there is shown two upright posts 1 which are interconnected at their upper end by a transverse member 2. On the facing sides, each of

nal recess 3 which terminates at a specified point below the transverse member 2. The recess 3 in each post near its point of termination is inclined toward one front face 60 of the post and opens onto the latter at which point the recess communicates with the U-shaped member 4, the width between whose legs is substantially the same as the width of the recess 3. The legs 5 and 6 65 of the U-shaped member are made arcuate in shape and the free end of the leg 5 is inset in the post 2 and attached thereto by an appropriate lag screw 7. The free end of the leg 6 is inset in the side wall of the recess 3 and appropriate flat head bolt 8 passes through this lag and through to the opposite face of the post, the threaded end of this bolt receiving a nut 9 which is set down against the post and serves to hold 70 the lag in firm attachment thereto. The U-shaped member 4 comprises essentially an extension of the recess 3, the two combined being a track way for the gate 10. The legs 5 and 6 of the U-shaped member are 75 so formed at their point of connection as to provide a depression 11 at the terminus of the track way.

The gate 10 is adapted for vertical movement in the two recesses 3 and to facilitate 85 this movement, it is provided at each end at the top and bottom with pintles 12, each of which carries a roller 13 which is adapted to roll in the recess 3 and in the track way formed by the U-shaped member 4. 90

The gate 10 is further provided on one side and at the bottom and adjacent the lower rollers 13 with eye bolts 14 to each of which there is attached one end of the cable 15 the latter being trained over a 95 sheaf 16 rotatably mounted on a support 17 carried by the post 1 near its top. The other half of the sheaf is provided with a guard 18 to insure the cable's sitting on the sheaf. Each cable 15 at the end remote 100 from that connected to the gate, is provided with a counter-weight 19, the two counter-weights being slightly less than the weight of the gate, so that the latter may assume the position of closure as the result of the 105 attraction of gravity. It will be observed that the sheaves 16, the cables 15 and their attendant parts are positioned on that side of the gate structure opposite that on which the U-shaped members 4 obtain.

On either side of the gate structure and projecting in opposite directions therefrom,

there are arms 21 which are braced against lateral displacement by the members 22 and further braced by the members 23 to resist the force imposed upon them when opening 5 the gate. It will be observed that the two arms 21 are so positioned as to be on the right when facing the gate from either side.

At substantially the longitudinal center of the transverse member 2, and on the bottom 10 face thereof, there are attached two pulleys 20. At the extreme end of the arms 21 there are also attached the pulleys 24 and at a slight distance back from the end of the arms there are pulleys 25 attached. Cables 15 or chains 26 are trained over the pulleys 24 and 20 and connecting with the gate 10 at the bottom edge and at the longitudinal center thereof. These chains 26 are of sufficient length to permit their free ends to be reached 20 when the gate 10 is in the closed position. A pulley 27 is carried on the transverse member 2 on that face overlooking the U-shaped members 4 and is positioned in the vicinity of the pulleys 20 while another pulley 28 is carried on the underface of the transverse member 2 and in close proximity to the pulleys 20. Cables or chains 29 are trained over the pulleys 25 and connect at 25 one end with the top of the gate 10 near the longitudinal center thereof, one of these cables 29 being trained over the pulley 28 while the other is trained over the pulley 27. These cables 29 are made only long enough to place their free ends within reach when 30 the gate is in the open position. The free ends of the cables 29 are provided with weights 30 which serve to lower the free ends of these cables when the gate is raised. These weights also serve as a hand grip. 35 The free ends of the cables 26 are similarly provided, both carrying weights 31 at their free ends.

In the use of the invention, the gate 10 is of sufficient weight to more than balance the 40 counter-weights 19 and which therefore, normally remains in the position of closure. When it is desired to open the gate, the free end of the cable 26 may be pulled, the force necessary to open the gate being only 45 enough to overcome the difference in the weight of the gate and the combined weight of the counter-weights. The continued pulling on the cable 26, will, therefore, serve to elevate the gate toward the tops of the posts 50 1 and the rollers 13 at the top edge of the gate will enter and roll over the legs 5 of the U-shaped members 4 and will finally pass into the depression 11. When the top of the 55 gate enters the U-shaped members 4, it is thrown from its normal vertical position into a diagonal position, thus shifting its center of gravity with respect to this connection with the cables 15, thereby allowing the 60 counter-weights to overbalance the gate. The gate will thus be held and remain in the 65

open position as long as the upper rollers engage the recesses 11. With the raising of the gate to this open position, the free ends of this cable 29 are lowered toward the ground thus placing their weights 30 within 70 reach. Desiring to close the gate, it is only necessary to pull on either of the cables 29 with a sufficient force to disengage the rollers from the recesses 11 and to draw the gate back toward the vertical position upon reaching which, it will overbalance the counter-weights and drop by gravity to its position of closure. 75

It will be observed that the counter-weights and their attendant parts are held 80 to one side of the gate structure, so that the counter-weights will not impinge upon parts of the fence that may be attached to the post 1.

Inasmuch as the gate when raised moves 85 from a normal vertical position to a position preceding the horizontal, it is possible to obtain the ordinary under-clearance for the gate without making the posts 1 any higher than is usual with swinging gates, the posts 90 of which are provided with a transverse piece similar to the piece 2 and similarly positioned.

The invention having been described, what 95 is claimed as new and useful is:

1. A gate structure comprising two vertical posts having recesses formed in their facing sides and arranged longitudinally therein, arcuate U-shaped members attached to the posts and communicating with the recesses so that the legs of the U-shaped members in combination with the recesses form continuous track ways, the free ends of the U-shaped members being so shaped as to leave depressions at the ends of the track 100 ways, a gate provided with pintles at the bottom and top of each end, rollers journaled on the pintles and engaging the track ways, counter-weights for the gate, means for elevating the gate until the upper rollers 105 engage in the depressions at the end of the track ways, and means for releasing the rollers from engagement with said depressions.

2. A gate structure comprising two vertical posts having recesses formed in their facing sides and arranged longitudinally therein, arcuate U-shaped members attached to the posts and communicating with the recesses so that the legs of the U-shaped members in combination with the recesses form continuous track ways, the free ends of the U-shaped members being so shaped as to leave depressions at the ends of the track ways, a transverse member connecting the 110 upper ends of the posts, a gate provided with pintles at the bottom and top of each end, rollers journaled on the pintles and engaging the track way, counter weights for the gate, an arm extending from the upper 115

end of each post, the two arms being disposed in opposite directions on each side of the gate structure, pulleys carried by the transverse member, pulleys carried at the 5 ends of the arms and at points a specific distance back from the ends, cables trained over the pulleys at the end of the arm, over certain of the pulleys on the transverse member

and with the bottom of the gate, and other cables trained over the pulleys positioned 10 back from the ends of the arms, over the remaining pulleys on the transverse member and connecting with the top of the gate.

In testimony whereof I affix my signature.

ORMUS E. BROWER.
